CLAIM

The ornamental design for a cosmetic protection mask as shown and described.

DESCRIPTION

FIG. 1 is a front, top and right-side perspective view of a first embodiment of a cosmetic protection mask, shown in an environment of use;

FIG. 2 is a front view thereof;

FIG. 3 is a right-side view thereof;

FIG. 4 is a top view thereof;

FIG. 5 is a bottom view thereof;

FIG. 6 is a perspective view of a second embodiment of a second embodiment of a cosmetic protection mask; and,

FIG. 7 is a rear view of the first embodiment of a cosmetic protection mask, shown with environment removed.

The broken lines are shown for the purpose of illustrating environmental subject matter only that forms no part of the claim.

1 Claim, 7 Drawing Sheets
